UNITED STATES PATENT OFFICE

PAUL HIDEGL, OF PITTSBURGH, PENNSYLVANIA, ASSIGNOR OF ONE-HALF TO
ALEXANDER NAGY, OF BISHOP, PENNSYLVANIA.

RAIL-JOINT.

1,162,358.

Specification of Letters Patent.

Patented Nov. 30, 1915.

Application filed May 17, 1915. Serial No. 28,796.

To all whom it may concern:

Be it known that I, PAUL HIDEGL, a subject of the King of Hungary, residing at Kilbuck Station, Pittsburgh, in the county of Allegheny and State of Pennsylvania, have invented certain new and useful Improvements in Rail-Joints, of which the following is a specification.

This invention relates to certain new and useful improvements in rail joints.

An object of the present invention is to provide a rail joint of the scarf type and in which the meeting ends of the rails are interlocked in such manner as to obviate the use of fastening bolts, fish plates or other fastening means at the joint, and which connection will securely lock the rail ends in operative position.

A further object of the invention is to provide a rail joint simple in construction and which may be easily joined together and held in such position by a key associated with the tread portion thereof.

With the above general objects in view and others that will appear as the nature of the invention is better understood, the same consists in the novel construction, combination and arrangement of parts to be herein-after more fully described and then claimed.

In the accompanying drawings which show the preferred embodiment of the present invention and to which reference is had herein by like characters designating corresponding parts throughout the several views:—Figure 1 is a side elevational view of a portion of two meeting rail ends constructed in accordance with the present invention. Fig. 2 is a top plan view of the same. Fig. 3 is a cross-sectional view taken on line III—III of Fig. 1. Fig. 4 is an enlarged perspective view of one of the rail ends, and, Fig. 5 is a detail perspective view of the locking key.

Referring more in detail to the accompanying drawings, the reference numeral 10 designates supporting ties of the usual construction, while the rail fastening spikes 11 are also indicated of the usual type. Mounted upon the ties 10 are the rails with the meeting ends thereof designated 12 and 13. The construction of each end of the rail will be hereinafter described.

The rail end 12 includes the tread portion 12' having the contacting end thereof cut-away to provide a downwardly project-

ing portion 14, which portion is cut inwardly as at 15 to provide a projecting nose 16. The web portion of the rail 12 is similarly constructed, with the contacting forward portion 17, an in-cut portion 18 and a nose portion 19. A second downwardly projecting portion is designated 20 and is similarly cut as at 21 to provide the rearwardly directed portion 22, and the remaining portion 23 of the web of the rail 12 extends 65 downwardly to the adjacent tie 10. The other rail end 13 is complementally constructed relative to the rail end 12 and includes the tread portion 13'. The tread portion 13' is provided with a transverse cut-away portion 24 having an under cut portion 25 to provide an overhanging ledge or nose portion 26, the upper wall 27 of the nose portion being disposed in the plane of the tread of the rail end. This portion 70 27 of the tread 13' and a part of the web of this rail end are cut-away as at 28, and further undercut as at 29 to provide a second overhanging nose portion 30 while a similarly constructed upstanding portion 31 75 80 is formed in the web of this rail and includes the projecting nose portion 32 and the undercut portion 33.

In assembling the meeting rail ends, the same are positioned side by side and moved 85 toward each other so that the adjacent noses and cut-away portions of each rail will register and interlock as indicated in Fig. 1. The rails are held in this interlocked position by the usual spikes 11 and to further prevent accidental movement or displacement of these interlocked ends, I prefer to provide registering recesses 34 in the rail treads to constitute a seat for the locking key 35 shown in Fig. 5. By inserting the key 35 90 95 within the recesses 34, lateral movement of the rail ends 12 and 13 is prevented, while the interlocked portions of the rail tread and web sections prevent longitudinal movement of the rails.

What I claim as new is:—

A rail joint including a pair of meeting rail ends, one of which is cut away from the base upward to provide a series of downwardly depending staggered portions in spaced relation longitudinally of the rail and each having a nose portion directed backward toward the rail, the remaining rail end being cut away from the tread downward to provide a staggered series of up- 105 110

standing portions spaced longitudinally to fit the spaces adjacent the noses of the first rail end and provided further with a series of noses interlocking with the first series of 5 noses, said rail ends being provided with opposed recesses extending longitudinally of their treads and opening into each other, and a key fitted in said recesses to prevent

lateral movement of one rail end with respect to the other. 10

In testimony whereof I affix my signature in presence of two witnesses.

PAUL HIDEG.
